UNITED STATES PATENT OFFICE.

THOMAS JENSEN, OF ARENDAL, NORWAY.

PLATE-SHEARS.

SPECIFICATION forming part of Letters Patent No. 632,351, dated September 5, 1899.

Application filed December 6, 1898. Serial No. 698,435. (No model.)

To all whom it may concern:

Be it known that I, THOMAS JENSEN, a citizen of the Kingdom of Norway, residing at Arendal, Norway, have invented Improvements in Plate-Shears, of which the following is a specification.

My invention relates to the features of structure and arrangement hereinafter fully described, and pointed out in the claims.

- 10 In the drawings, Figure 1 is a side view, Fig. 2 a plan, and Fig. 3 a perspective, of the tool in the act of cutting a plate. Fig. 4 is an end view of the shears. Figs. 5 and 6 are detail views.
- 15 The shears comprise the two limbs *c c'*, pivoted together at one end *f* and having the cutting blades or jaws *e e'* at their other ends. Each of these limbs has a laterally-arranged portion, (marked, respectively, *pp'*), and these 20 form a recess or socket between them, as indicated in Fig. 2. An arm *d* is pivoted at *b''* to the portion *p'*, and this arm is bent, as shown in Fig. 6, so that its ends are out of line. The upper end of the arm *d* lies in the 25 depression or recess formed by the laterally-bent part *p* of the arm *c*, and it has a recess in its edge, which receives the pivot projection *b'* of the lever *a*, which is pivoted to the member *a* at the part *p* that is within the depression or recess formed by the laterally-extending portion. The lower bent end of the 30 arm *d* is pivoted in the recess of the member *c'* at *b''*, as before stated. It will be seen that the pivot *b'* is integral with the lever *a* and 35 simply engages the notch in the arm *d*.
- It will be seen from Fig. 2 that the cutting edge of *e*, the inner upper face of the arm *d*, the face of pivot *b'*, the inner side of lever *a*, and inner side of member *c* all lie in the same 40 plane, while the face of the jaw *e'*, the face of the lower end of the bent arm *d*, and the

inner face of the member *c'* all lie in the same plane. By this arrangement the advantage is gained that there are no projecting parts presented which will work against the edge 45 of the metal plate during the cutting, but the plate will pass straight through the shears without having its edge deformed in any way.

Having now described my invention, what I claim as new, and desire to secure by Letters 50 Patent, is—

1. Plate-shears comprising the limbs *c, c'*, having laterally-arranged portions *p, p'*, forming a recess or socket between them, an arm *d* having its upper and lower parts out 55 of line, the lower part of said arm being pivoted in the recess of the member *c'* and the upper part of the said arm lying in the recess of the other member and the lever *a* pivoted to the member *c* and connected with the 60 arm *d*, substantially as described.

2. In combination in a plate-shears, the two members each having a recess in its inner face, a lever pivoted to the one member and an arm pivotally connected with said lever and 65 with the other member, said arm being bent intermediate of its length, substantially as described.

3. In combination, the two members having the recesses forming a socket between them 70 and the bent arm therein pivoted to one member and having a notch in its edge, a lever pivoted to one of the members the said lever having a pivot *b'* extending therefrom to engage the socket, substantially as described. 75

In witness whereof I have hereunto set my hand in presence of two witnesses.

THOMAS JENSEN.
